E. C. Midgley

By Samuel Herrick

Attorney

UNITED STATES PATENT OFFICE.

ERNEST C. MIDGLEY, OF UNION, NEW YORK.

GLARE SCREEN.

Application filed May 8, 1924. Serial No. 711,805.

To all whom it may concern:

Be it known that ERNEST C. MIDGLEY, citizen of the United States, residing at Union, in the county of Broome and State 5 of New York, has invented certain new and useful Improvements in Glare Screens, of which the following is a specification.

This invention relates to a glare screen adapted to be attached to the wind shield 10 of automobiles to shield the eyes of the driver from the glare of the headlights of approaching automobiles.

It is a primary object of the invention to provide simple and economical means for 15 holding the glare screen in place upon the wind shield.

Further objects and advantages of the invention will be set forth in detailed description which follows.

20 In the accompanying drawing:

Fig. 1 is an inner elevation of a portion of a wind shield having the invention applied thereto.

25 Fig. 2 is a horizontal sectional view upon line 2—2 of Fig. 1.

Fig. 3 is a horizontal sectional view through one of the vacuum cups hereinafter described and:

30 Fig. 4 is a vertical sectional view through one of said vacuum cups the same being shown partly in elevation.

Like numerals designate corresponding parts throughout the several figures of the drawing.

35 In the drawing A designates the upper section of a conventional wind shield. The glare screen proper consists of a web which may be wire gauze, loosely woven textile fabric or other semi-transparent material.

40 At each end of the web 5 there is provided a loop or bail 6, one leg of which passes through the end of the web and the other leg of which passes through a channel 7 formed in a boss 8, of a vertically elongated, vacuum

45 cup 9. A rib 10 lying vertically of the cup constitutes a handle or grip whereby it may be grasped and forced into contact with the inner face of the glass of the wind shield.

The device of the invention is so simple in construction and so easily applied that the 50 driver finds no difficulty in readily putting it in place for use when driving at night and, if desired, removing it during the day, though it may be left in place if desired.

It is to be understood that the invention is 55 not limited to the precise construction set forth but that it includes within its purview whatever changes come within either the terms or the spirit of the appended claims.

Having described my invention what I 60 claim is:

1. A glare screen comprising an elongated web of flexible and foraminous fabric, an elastic vacuum cup at each end thereof, said vacuum cups being substantially triangular 65 in transverse cross-section and being elongated in the direction of the width of the web of fabric, elongated ribs extending along the inner sides of the vacuum cups said ribs having openings formed therethrough from end to end, looped portions formed at the ends of the fabric and wire loops which extend through the looped portions of the fabric and through the openings of the said ribs. 70

2. A glare screen comprising an elongated web of flexible and foraminous fabric, an elastic vacuum cup at each end thereof, said vacuum cups being substantially triangular 75 in transverse cross-section and being elongated in the direction of the width of the web and each having an elongated rib along the apex of the triangle, elongated ribs lying along the inner sides of the said vacuum cups and substantially equal in length to the width of the foraminous fabric and wire loops having portions which extend entirely through the last named ribs and through looped portions formed at the ends of the foraminous fabric. 80

In testimony whereof he affixes his signature in the presence of two witnesses.

ERNEST C. MIDGLEY.

Witnesses:

JOHN M. PAYNE,

FRANK E. DAY.
